RAILWAY TRACK LUBRICATING APPARATUS

Thomas E. Rodman, Glencoe, and Harold G. Warr, Park Ridge, Ill., assignors, by direct and mesne assignments, to Poor & Company, Chicago, Ill., a corporation of Delaware

Application March 31, 1941, Serial No. 386,146

1 Claim. (Cl. 184—3)

This invention relates to railway track lubricating apparatus, and has particular reference to improvements in that type of apparatus which supplies to the inner side of the head of a railway rail, at curves and other necessary locations, a lubricant to be picked up and distributed along the rail by the flanges of locomotive and car wheels to reduce frictional wear and noise due to the wiping action of the wheel flanges against the rail head.

The invention relates more particularly to improvements in track rail lubricating apparatus of the known type comprising a lubricant reservoir, a lubricant distributing device located at the side of the rail to be lubricated and connected with said reservoir, a pump for supplying lubricant from said reservoir to said distributing device, and means operable by the passing of locomotive and car wheels over a given part of the track to actuate said pump. Moreover, the invention relates still more particularly to track rail lubricating apparatus of the type mentioned in which the operative connection between the pump and its actuating means is of the closed-circuit, hydraulic type.

Generally speaking, the object of the present invention is to provide an exceptionally simple, inexpensive, practical and thoroughly reliable track rail lubricating apparatus of the type mentioned in which the lubricant pump preferably, but not necessarily, is located within and protected by the lubricant reservoir and is removably carried by the cover of the lubricant reservoir for ready removal therefrom for cleaning, repair, part-replacement or other purposes.

Another object of the invention is to provide a lubricating apparatus of the type mentioned embodying provision to compensate for expansion and contraction of the liquid contained in the closed circuit between the pump and the pump actuating means, thereby to insure proper functioning of the apparatus despite changes in temperature of the ambient air.

With the foregoing and other objects in view, which will become more fully apparent as the nature of the invention is better understood, the same consists in the novel features of construction, combination and arrangement of parts as will be hereinafter more fully described, illustrated in the accompanying drawing and defined in the appended claim.

In the accompanying drawing:

Figure 1 is a cross sectional view through a track rail and lubricating apparatus therefor con-

structed in accordance with one practical embodiment of the invention; and

Figure 2 is a detail cross sectional view illustrating an alternative form of pump actuating means.

Referring to the drawing in detail, first with particular reference to the embodiment of the invention illustrated in Fig. 1, A designates a railway rail, B designates a cross tie supporting said rail, C designates a lubricant reservoir which may be sunk in the ground or otherwise conveniently located adjacent to said rail A, D designates a lubricant distributing device mounted at the inner side of the rail A to be supplied with lubricant from the reservoir C, E designates a pump for forcing lubricant from the reservoir C to the lubricant distributing device D, and F designates a device, operable by the passage of train wheels over the rail A, to actuate the pump E. The action here involved is that the lubricant will be applied to the side of the rail head and the face of the wheel flange from the distributing device or bar and in turn applied to the rail head by successive revolutions of the wheel. These spots of lubricant are then spread out by contact of successive wheels and also by reason of the fact that wheels vary in diameter. This process is continued until, at a point a number of rail lengths beyond the lubricator, a continuous coating of lubricant is spread on the face of the rail flange.

The lubricant reservoir C is provided with a cover 10 which may be lifted to permit filling of said reservoir, and in accordance with the practical embodiment of the invention illustrated in Fig. 1 the pump E is carried by said cover and depends therefrom into said reservoir, being preferably removably mounted on said cover for cleaning, repair or other purposes through the instrumentality of a plug 11 threaded into a preferably central opening in said cover.

The pump E comprises a cylinder 12 threaded at its upper end into the plug 11 and depending from said plug to a point preferably near the bottom of the reservoir C. This cylinder may be of any suitable diameter and at its upper end is closed by the plug 11, while at its bottom it is in communication with the reservoir C under the control of a suitable check valve 13 which opens toward said cylinder and closes toward said reservoir.

In the plug 11 and in communication with the upper end of the cylinder 12 is a lubricant outlet duct 14 which is connected with the lubricant distributing device D by a suitable con-

duit 15, while suitably associated with the duct 14 is a check valve 16 which closes toward said cylinder 12 and opens toward said lubricant distributing device.

Suitably mounted in the cylinder 12, as upon a head 17 carried by the lower end of a pipe section 18 suitably supported at its upper end by the plug 11 and extending therethrough, is an expandable and contractable bellows-piston 19 which, at its upper end, is in communication with said pipe section 18 and which otherwise is closed, being completely closed with respect to said cylinder. Suitable ducts or passageways 20 in the head 17 permit flow of lubricant therethrough from the cylinder space at the lower side thereof to the cylinder space at the upper side thereof. It will thus be apparent, assuming that the reservoir C contains lubricant and that lubricant fills the cylinder 12, the conduit 15 and the lubricant distributing device D, that upon expansion of the bellows-piston 19 lubricant will be displaced from said cylinder 12 and forced through the conduit 15 to the lubricant distributing device D and from said lubricant distributing device to the rail, since the check valve 16 will prevent the lubricant from being forced from said cylinder to the reservoir C. On the other hand, it will be equally apparent that upon contraction of the bellows-piston 19, lubricant will be drawn into the cylinder 12 from the reservoir C, since the check valve 16 will prevent lubricant from being drawn from the conduit 15 into said cylinder. In other words, it is apparent that each time the bellows-piston 19 is expanded, lubricant will be delivered to the lubricant distributing device D, while each time said bellows-piston is contracted replenishing lubricant will be drawn into the cylinder 12 from the reservoir C.

Slidable in the lubricant reservoir C is a follower 10^a which serves constantly to urge lubricant contained in said reservoir toward the bottom thereof to replace lubricant drawn from said reservoir by the pump E.

The pump actuating device F illustrated in Fig. 1 is of a type to be actuated by the wave motion imparted to the rail A due to the passage of train wheels thereover. To this end said device comprises a bellows 21 which is supported at its lower end against downward movement and which is suitably associated at its upper end with the rail so as to be contracted in response to downward deflection of the rail due to passage of rolling stock thereover, suitable spring means 22 being provided to expand or elongate said bellows when the rail rises following downward deflection thereof. A suitable conduit 23 connects the pipe 18 with the interior of the bellows 21, preferably at the bottom of the latter, and said bellows 21 otherwise is closed. Moreover, the closed-circuit system comprising the bellows-piston 19, the pipe 18, the conduit 23 and the bellows 21 is filled with a suitable liquid such, for example, as light oil. It will thus be apparent that each time the rail A is deflected downwardly the bellows 21 will be contracted and liquid will be forced therefrom to the bellows-piston 19, with the result that said bellows-piston 19 will be expanded and will force lubricant from the cylinder 12 to the lubricant distributing device D. It will be equally apparent that each time the rail A rises following downward deflection thereof, the spring means 22 will expand the bellows 21 with the result that liquid will be drawn from the bellows-piston 19 and the latter thereby will be contracted, thus effecting a

replenishing supply of lubricant to the cylinder 12 from the reservoir C.

According to the specific embodiment of the invention illustrated in Fig. 1 the bellows 21 and its associated spring means 22 are contained within a protective casing 24 which is supported by a bracket 25^a which in turn is supported by the tie B. The bellows 21 rests at its bottom on the bottom of said casing 24 and the spring means 22 is in the form of a coil spring surrounding said bellows and interposed between the bottom of said casing 24 and an outwardly extending flange of a cap-piece 25 carried by the bellows 21 at the upper end thereof, said cap-piece having a stem 26 extending through an opening in the top of the casing 24 and engaged at its top with the under face of the rail. Thus, when the rail A is deflected downwardly the bellows 21 is contracted and the spring 22 is compressed. On the other hand, when the rail A rises following downward deflection thereof, the spring 22 acts to elongate or expand the bellows 21.

In filling the closed-circuit system comprising the bellows-piston 19, the bellows 21 and the connections between the same, the bellows-piston 19 is mechanically expanded to such an extent that when the ambient temperature drops to the lowest degree expected to be encountered at the location of the apparatus, the liquid in said system 30 will still fill it. Elongation and contraction of the bellows-piston 19 will compensate for expansion and contraction of the liquid due to ambient temperature changes and the system thus will function in the same manner despite ambient temperature changes within all ordinary or expected limits.

Instead of employing actuating means for the pump E in the form of a device F such as is illustrated in Fig. 1 to be actuated in response to wave motion of the rail A, equivalent pump actuating means, such as the means designated generally as F' in Fig. 2 of the drawing, may be provided to be actuated by train wheels passing over the rail A.

As in the case of the device F illustrated in Fig. 1, the device F' comprises a bellows 21' housed by a protective casing 24' and resting at its bottom upon the bottom of said casing; a flanged cap-piece 25' at the top of said bellows having a stem 26' extending upwardly therefrom through an opening in the top of the casing 24', and a bellows-expanding coil spring 22' surrounding said bellows and interposed between the bottom of said casing 24' and the flange of said cap-piece, said bellows 21' being internally connected at its bottom with the pump E by a conduit 23'. However, instead of the device F' being mounted to have its stem 26' depressed by downward deflection of the rail A, as in the case of the device F illustrated in Fig. 1, said device F' is suitably mounted at the side of the rail A with its stem 26' in the path of the train wheels passing over said rail so that said stem is depressed by the train wheel. In other respects the device F' operates the same as the device F.

To variably predetermine the amount of contraction of the bellows 21' by train wheel depression of the stem 26', thus to variably predetermine the amount of expansion of the bellows-piston of the associated pump and, consequently, the amount of lubricant which will be delivered to the device D each time the bellows 21' is contracted, one or more spacing elements 27' may be interposed between the cap-piece 25' and the top 75 of the casing 24'.

Without further description it is thought that the features and advantages of the invention will be readily apparent to those skilled in the art, and it will of course be understood that changes in the form, proportion and minor details of construction may be resorted to, without departing from the spirit of the invention and scope of the appended claim.

We claim:

Track rail lubricating apparatus including a lubricant reservoir, a lubricant distributing device for the track rail, a removable pump unit comprising a supporting head carried by the reservoir cover and provided with a valved outlet and with a pump fluid inlet, a pump chamber within the reservoir suspended at its upper end from the supporting head and provided at its lower end with a valved lubricant inlet communi-

cating with the reservoir, the upper end of said pump chamber being in lubricant delivery communication with the valved outlet in said supporting head, a stationary ported member mounted within the pump chamber intermediate the upper and lower ends of the chamber and providing communication therebetween, and an expandible and contractible bellows-piston carried by said stationary member and in communication only with said fluid inlet of said pump unit supporting head, a piping connection between the valved outlet of the said supporting head and the lubricant distributing device, and a bellows-type actuator in closed fluid circuit communication through said pump fluid inlet with the bellows-piston within the pump chamber.
